Primary Examiner — Martie K Holtje(74) *Attorney, Agent, or Firm* — Gary J. Cunningham(57) **CLAIM**

The ornamental design for a wrist-worn display, as shown and described.

DESCRIPTION

FIG. 1 is a front perspective view of a wrist-worn display showing our new design;

FIG. 2 is a rear perspective view thereof;

FIG. 3 is a rear view thereof;

FIG. 4 is a front view thereof;

FIG. 5 is a first side view thereof;

FIG. 6 is a second side view thereof;

FIG. 7 is a top view thereof; and,

FIG. 8 is a bottom view thereof.

The structural features depicted by broken lines have been shown for the purpose of illustrating portions of the wrist-worn display that form no part of the claimed design.

1 Claim, 6 Drawing Sheets(56)
